UNITED STATES PATENT OFFICE.

FRANK E. HOUSH, OF BOSTON, MASSACHUSETTS, ASSIGNOR TO THE HOUSH COMPANY, OF BOSTON, MASSACHUSETTS, A CORPORATION OF MAINE.

EASEL.

SPECIFICATION forming part of Letters Patent No. 772,513, dated October 18, 1904.

Application filed April 23, 1904. Serial No. 204,517. (No model.)

To all whom it may concern:

Be it known that I, FRANK E. HOUSH, a citizen of the United States, and a resident of Boston, in the county of Suffolk and State of Massachusetts, have invented new and useful Improvements in Easels and the Like, of which the following is a specification.

My invention is of that class in which a mount is supported by an easel-leg; and its object is to provide an improved article of this class, and particularly to provide a cheap and convenient means to support the mount on either its end or side and to hold it securely in either position at different angles.

15 My improved easel comprises a slotted mount having a separable leg constructed to engage the slotted mount through a slot-and-tongue frictional connection between the mount and leg so that the two are detachably connected and the leg can be shifted about on the back of the mount to support the latter either on its end or side and at different angles.

20 A feature of my invention resides in the construction of the detachable leg, which in its best form is made of a single strip of material folded into a triangular shape and provided at each end with a tongue, which is adapted to be inserted into a slot of the mount and to establish the slot-and-tongue frictional connection above referred to. This construction is simple, convenient, and gives great strength to the leg, the lower side of the triangle acting as a stay and preventing the supporting member from sliding under the weight of the 25 mount. Moreover, by folding the strip at different points throughout its length the mount may be securely supported in different angular positions, or this result may be obtained by inserting the tongues of the leg in

30 different slots of the mount, thereby obtaining any desired angle for the mount and overcoming the objection to former easels of this class, in some of which the leg was so made that the easel could be supported only at one angle, while in others, though it was possible to attach the leg so as to support the easel at different angles, yet, as a practical matter, the leg could be used to support the mount se-

curely in but one position. The convenience of this form of leg for packing and the like is 50 obvious, made, as it is, from a single flat strip, as is also the economy in manufacture.

In the accompanying drawings, illustrating an embodiment of my invention, Figure 1 is a rear elevation of my easel. Fig. 2 is a vertical section on the line 2 2 of Fig. 1. Fig. 3 is a plan view of the supporting-leg broken away at the center to save space. Fig. 4 shows a modified form of the body of my easel, and Fig. 5 shows a modified form of the supporting-leg.

The mount of my improved easel is preferably composed of two parts A and B of cardboard, paper, or other suitable material fastened together. This mount may be of any 65 desired shape or size, but I have shown it rectangular. The rear part B is provided with longitudinal slots 1 and latitudinal slots 2, and in the preferred form of my invention (shown in Fig. 1) these slots are arranged in 70 two series, which cross one another at the center of the mount.

C is a supporting-leg in its best form made of a single strip of cardboard or other suitable material and provided at each end with a 75 tongue *a* and shoulders *b* at the base of the tongue. The leg C may be made of a single piece of material or made of three separate sections X Y Z fastened together, as shown in Fig. 5; but preferably it is of a single piece 80 folded into a triangular form, as shown in Fig. 2. The tongues *a* are of such size that they fit into the slot in the part B, forming a slot-and-tongue frictional connection between the mount and the leg, through which the leg holds 85 the mount permanently in position.

If the mount is to be supported on its side, the leg is separated from the part B and shifted into the position shown by dotted lines at D in Fig. 1, the tongues *a* being placed in one 90 or more of the longitudinal slits or slots in the part B. If it is to be supported on its end, the tongues are placed in one or more of the latitudinal slits or slots, as shown in full lines in Fig. 1. It is obvious that different angular 95 positions may be readily obtained either by

shifting both tongues *a* from one slit or slot to the next slit or slot of that series above or below or by inserting one tongue in one slit or slot of one of the series and the other tongue 5 in a different slit or slot of the same series.

What I claim is—

1. The combination of a mount with longitudinal and latitudinal slots and a detachable leg inserted at one end into one of the slots 10 to form a slot-and-tongue frictional connection between the mount and leg, substantially as described.

2. The combination of a slotted mount and a detachable leg formed as a triangle substantially as shown whose opposite ends are inserted into the slot to form a slot-and-tongue frictional connection between the mount and leg substantially as described. 15

3. The combination of a slotted mount and a detachable leg bent so that its opposite 20 ends are inserted into the slot to form a slot-and-tongue frictional connection between the mount and leg, substantially as described.

4. The combination of a slotted mount and a detachable leg having angular bends in its 25 length whose opposite ends are inserted into the slot to form a slot-and-tongue frictional connection between the mount and leg, substantially as described.

Signed by me at Boston, Massachusetts, this 30
21st day of April, 1904.

FRANK E. HOUSH.
